(57) **CLAIM**

The ornamental design for an electric carving knife, as shown and described.

DESCRIPTION

FIG. 1 is a perspective view of an electric carving knife according to the present invention;

FIG. 2 is a first side view of the electric carving knife of FIG. 1;

FIG. 3 is a second, opposite view of the electric carving knife of FIG. 1;

FIG. 4 is a top view of the electric carving knife of FIG. 1; FIG. 5 is a bottom view of the electric carving knife of FIG. 1;

FIG. 6 is a first end view of the electric carving knife of FIG. 1; and,

FIG. 7 is a second, opposite end view of the electric carving knife of FIG. 1.

The broken lines showing a knife blade in FIGS. 1–5 are for illustrative purposes only and form no part of the claimed design.
